UNITED STATES PATENT OFFICE.

RUSSELL C. MAHON, OF HIGHLAND PARK, MICHIGAN.

ROOF SUMP.

Application filed June 21, 1924. Serial No. 721,426.

To all whom it may concern:

Be it known that I, RUSSELL C. MAHON, a citizen of the United States, residing at Highland Park, in the county of Wayne and State of Michigan, have invented a new and useful Roof Sump, of which the following is a specification.

This invention relates to sumps and more particularly to roof sumps.

10 It is the object of the invention to provide a sump having a discharge connection with a suitable drain pipe and adapted to exclude foreign matter from said pipe, and to be readily removed to facilitate cleaning either 15 of the sump or of said pipe.

A further object is to provide a sump comprising a catch basin having a drain pipe leading therefrom, and a cover member for said basin rotatively seated upon the 20 latter and removably only in one position of its rotation.

Still another object is to seat the rotatable cover of said basin in such a manner as to secure it to some extent from rotation when 25 properly positioned for use.

These and various other objects are attained by the construction hereinafter described and illustrated in the accompanying drawing wherein,

30 Fig. 1 is a plan view of the improved sump showing a portion of a roof or the like, drainage of which is effected by said sump.

Fig. 2 is a vertical sectional view of the 35 same, taken upon line 2—2 of Fig. 1.

Fig. 3 is a sectional detail on line 3—3 of Fig. 1.

In these views the reference character 1 40 designates a roof or other surface to be drained, and 2 is a stand pipe through which such drainage is effected. The invention establishes the upper end of said pipe in screw-threaded connection with the bottom of a catch basin 3 which is set into 45 the roof 1 and is formed with an external annular flange 3^a at its top, which is arranged in a flush relation with the roof surface to be drained. The basin 3 is provided with a cover member 4 having a plurality of openings 4^a therein for admission 50 of drainage from the roof 1. It is usual in the case of roof sumps to provide a cover member of a raised type as shown in Fig. 2, but it is to be understood that the particular shape of the cover member 55 will depend upon the use to which the sump

is put. Thus, if the construction were applied to a floor rather than a roof, it would be preferable to employ a substantially flat cover member. At its base the cover 4 is formed with a peripheral outstanding flange 5 adapted to seat upon a plurality of lugs 6 integral with the basin 3 interiorly of the latter.

To latch said cover in its position of use, the flange 5 is formed with a plurality of radial notches 7 preferably equidistant, and the basin 3 is formed with corresponding raised lugs 8 slightly overhanging the mouth of said basin so that registration of the notches 7 with the lugs 8 is a prerequisite to lowering of the cover to permit its base to enter the mouth portion of the basin 3 and engage the seating lugs 6. When such engagement has been established the 75 cover may be rotatively shifted to destroy registration of the notches 7 with the lugs 8, so that a consequent removal of the cover from its position of use can be accomplished only after first rotating said cover to again 80 register said notches and lugs.

It is desirable to provide a definite position of use of the cover 4, in which position the notches 7 will be remote from the lugs 8, and such a position may be established by 85 forming the seating lugs 6 of a width slightly greater than that of the notches 7, and so locating said seating lugs that in the desired position of use of the cover said notches will register with the lugs 6 and allow the upper 90 ends of said lugs to engage to some extent in said notches (see Figure 3) to restrain the cover from rotating until freed from the described engagement by slightly lifting said cover. It is preferred to positively 95 limit rotation of the cover when shifted to its position of use by forming upon the flange 5 upstanding projections 9, which are engaged with the lugs 8 to limit further rotation of said cover when the latter has 100 been shifted to register its notches 7 with the seating lugs.

It is a feature of the described invention that the cover 4 is very quickly and easily removable from the catch basin 3 provided it is properly manipulated for the purpose of removal, while provision is made to quite securely prevent accidental removal of said cover or its removal by unauthorized persons unfamiliar with the necessary manipulation.

The construction furthermore is exceed-

ingly simple and adapted for manufacture at low cost.

What I claim is:

1. A sump comprising a catch basin and a cover member therefor, a lug upon said basin overhanging its mouth portion, a flange upon said cover member notched for registration with said lug in engaging the cover member with the basin, and a seating lug upon the basin proportioned to partially engage in said notch upon rotation of the cover member from the position of its initial engagement with its seat.
2. A sump comprising a catch basin and a cover member insertible into the mouth portion of said basin, a seating lug for said cover member carried by the basin interiorly thereof, a securing lug for said cover member upon said basin spaced from said seating lug circumferentially of the basin and overhanging the latter, said cover member having a peripheral notch for registration with said securing lug in initially engaging the cover member with its seat, and said notch being further engageable with said seating lug upon a rotative actuation of the cover member from its initial seating position to establish a position of use of said cover member, and a stop projection formed upon said flange and engageable with said securing lug to limit rotation of the cover member from its initial seating position to its final position of use.
3. A sump comprising a catch basin and a cover member insertible into the mouth portion of said basin, a seating lug for said

cover member carried by the basin interiorly thereof, a securing lug for said cover member upon said basin spaced from said seating lug circumferentially of the basin and overhanging the latter, said cover member having a peripheral notch for registration with said securing lug in initially engaging the cover member with its seat, and said notch being further engageable with said seating lug upon a rotative actuation of the cover member from its initial seating position to establish a position of use of said cover member, and a stop projection formed upon said flange and engageable with said securing lug to limit rotation of the cover member from its initial seating position to its final position of use.

4. A sump comprising a catch basin and a cover member therefor, a lug upon said basin overhanging its mouth portion, a flange upon said cover member notched for registration with said lug, in engaging the cover member with the basin, and a stop projection upon said cover member, above said flange, engageable with said lug through rotation of the cover member when engaged with the basin, limiting such rotation.

In testimony whereof I sign this specification.

RUSSELL C. MAHON.
